United States Patent Office.

AMERICAN GERNER BOILER COMPANY, OF NEW YORK, N. Y., ASSIGNEES
OF HENRY GERNER.

Letters Patent No. 73,595, dated January 21, 1868; reissue No. 4,186, dated November 29, 1870.

DIVISION B.

IMPROVEMENT IN STEAM-GENERATORS.

The Schedule referred to in these Letters Patent and making part of the same.

To all whom it may concern:

Be it known that HENRY GERNER, of the city of New York, county and State of New York, has invented certain new and useful Improvements in Steam-Boilers, of which the following is a specification, reference being had to the accompanying drawing forming part thereof.

Figure 1 represents a longitudinal central section thereof.

Figure 2 is a transverse section of the same, the line x x , fig. 1, indicating the plane of section and looking in the direction of the arrow opposite that line.

Similar letters indicate corresponding parts.

The invention relates to steam-boilers in which the products of combustion pass from the fire-place to the opposite end through a fire-flue or combustion-chamber within the boiler, and thence return to the front end through a separate flue, also within the boiler, and consists in combining within a boiler two fire-flues, one within the other, and each within a water-chamber, as represented in the drawing.

A represents a boiler-shell, the upper part of which may, if desired, be cut away, as shown in the drawing, and replaced by a semi-cylindrical drum, B ; giving thereby additional steam room.

This drum may be provided with an additional steam-dome, C .

In the interior of the shell A is a second shell, D , the diameter of which is sufficiently smaller than that of the shell A to leave room for the water-chamber a .

The upper part of the inner shell D is cut away and replaced by the shell E , the upper portion of which is also cut away, the two shells being united at their cut edges, as shown in the drawing.

This shell E is secured in place within the shell D , so as to leave between its under surface and the inner surface of the lower portion of the shell D a suitable

fire-flue or combustion-chamber, H , and its rear end is made to connect by one or more tubes, b , with the water-chamber a .

Within the shell E is placed and secured another shell, F , the diameter of which is such that an annular water-chamber, e , is left between it and the shell E .

The two shells E and F are represented in the drawing of a conical form, as being better than the cylindrical form, giving a more favorable heating action to the flame upon the walls of the flues, preventing the collection of sediment on the lower surface of the water-chamber e , and affording conveniently a larger space for the fire-place.

The interior of the shell F constitutes the return fire-flue.

The fire is made on the grate G , which is situated under the front end of the shell E , and the flames pass through the flue H to the jacket I , thence back through the flue F to the smoke-stack J .

Both the direct and return fire-flues H and F are each thus substantially enveloped by a water-chamber, exposing, when the boiler is in operation, a comparatively thin sheet of water to a large heating-surface, thereby generating steam with great economy of fuel and equally diffusing heat throughout the boiler.

What is claimed as new, and desired to be secured by Letters Patent, is—

A return longitudinal fire-flue, F ; within a direct longitudinal fire-flue, H , each fire-flue being within a water-chamber, a and e , and all within the boiler, substantially as described.
